UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

TWIN LAMP SOCKET.

Application filed February 4, 1924. Serial No. 690,340.

My invention relates to plural lamp sockets and in one of its broad aspects aims to provide a simple, inexpensive, easily assembled and highly effective plural lamp socket. Furthermore, my invention aims to provide a socket for this purpose which can readily be employed in connection with separately controlled circuits having a common return for supplying current to a plurality of lamps associated respectively with the said circuits, and with a single detachable wire-terminal plug.

In a more particular aspect, my invention relates to a multiple lamp socket adapted for use with lamps provided with metal casings grounded to one lamp terminal. For this purpose, my invention provides a simple socket construction employing the metal shell of the socket as the common return for the circuits from the lamps, and including a simple assembly and mounting for contacts respectively engaging the other terminals of the lamps. Furthermore, my invention provides a socket construction for this purpose in which the shell is composed of simple stampings, in which the stampings comprising the shell are secured to each other by the same fastening member which holds the contact-carrying insulating parts securely in the shell, in which the contacts are firmly held in position by the insulating parts without requiring auxiliary fastening elements and in which the various parts can readily be formed for disposing the lamps in various positions with respect to one another.

In lamps employed for signaling, as for example in vehicle lamps serving both as tail lamps and for stop signal indications, it is customary to dispose each of the signal lights in a separate compartment of a single casing and it is desirable to have the current supplied to the group of lamps from a single wire-carrying plug which can readily be detached from the body of the signal appliance. Signal lamps for such two-fold purposes are shown for example in U. S. Patent No. 1,475,296, issued to me on November 27, 1923; also in my copending application No. 638,660, filed May 12, 1923, of which latter application my present application is in part a division. This patent discloses a signal lamp in which each of the lamp bulbs has one end of its filament

grounded to the lamp casing while the other side of the circuit is carried to the axial lamp terminals by spring fingers mounted on a detachable wire terminal plug. While this arrangement is highly effective when the plug is attached, it has the disadvantage that it leaves the lamps loose when the plug is detached, so that they may be subject to a damaging amount of jarring and the lower of the lamps might even be jarred out of the socket and broken by its fall. Furthermore, the construction shown in my said patent necessitates the mounting within the lamp body of two separate socket shells, namely one for the two lamp bulbs and another for the terminal plug, which complicates the manufacture when applied to many designs of lamp assemblies.

My present invention aims to overcome the above mentioned objections by providing a multiple lamp socket in which the lamp-engaging spring contact fingers are continuously retained in the socket and in which current is conveyed to them by a standard type of a detachable wire terminal plug. It also provides a construction for this purpose which can be mounted in the lamp body in its entirety as a unit, and one in which the shell consists of two simple and counterpart metal stampings. Furthermore, it provides a multiple socket assembly in which the spring contact members are clamped against an interposed core or insulating body by a tube which insulates these contact members from the metal shell; in which the insulating core and the contact members have cooperating formations which prevent a relative shifting of the same when thus clamped; and in which all parts of this socket are firmly held in their proper relative positions by the single fastening member which secures the two parts of the shell to each other. Still further and also more detailed objects will appear from the following specification and from the accompanying drawings, in which drawings—

Fig. 1 is an elevation of a twin lamp-socket embodying my invention and designed for use with two incandescent lamps extending in alignment with each other but in opposite directions.

Fig. 2 is an enlarged central vertical and longitudinal section through the same.

Fig. 3 is a similarly enlarged section

through the same taken transversely of Fig. 2 with the lamps and wire-terminal plug detached.

Fig. 4 is an enlarged end view of the same socket, taken from the left hand end of Fig. 1.

Fig. 5 is an enlarged perspective view of the body assembly which consists of the insulating core, the pair of contact members 10 and the insulating tube which clamps these contact members to the core.

Fig. 6 is an enlarged perspective view of the insulating core.

Fig. 7 is an enlarged perspective view of one of the contact members.

Fig. 8 is a section similar to Fig. 3 but showing a socket arranged for holding two lamps at an angle to each other and oblique to the wire-terminal plug used for conveying 20 current to them.

In the embodiment of Figs. 1 to 7 inclusive, the socket of my invention has a substantially T-shaped shell composed of two cylinders adjoined so that one extends at 25 an angle to the other and is connected substantially to the middle of the said other cylindrical portion 1 which forms the stem of the T formation is provided at its free end with 30 bayonet slots 2 for interlocking with the usual lateral projections 28 upon the shell 3 of a wire terminal plug which has spring pressed plungers 4 and 5 projecting from its inwardly directed end and respectively 35 connected to the two separately controlled circuit wires 29 and 30. The other cylindrical portion 6 which forms the head or cross-bar of the T-formation has its ends equipped respectively with bayonet slots 7 40 and 8 for interlocking respectively with the usual lateral projections on the two incandescent lamps 9 and 10 which are to be employed for distinct signal indications.

Mounted in the shank portion 1 of the 45 shell is a body member comprising an insulating core 11 and having a pair of resilient contact members clamped to the same by an insulating tube 13 which fits slidably into the shank 1 of the shell. The insulating 50 core 11 has a pair of oppositely disposed lateral recess formations or channels extending longitudinally thereof for receiving the shank portions 14 and 15 of the two contact members respectively, each such recess 55 having lateral shoulder formations 16 engaging opposite edges of the contact member which is seated in that recess so as to prevent lateral movement of this contact member. The rear end of each contact 60 member is bent over the rear end of the insulating body radially inward of the latter so as to afford a contact tip adapted to be engaged by one of the spring-pressed plungers of the wire terminal plug 3. These 65 contact tips 17 and 18 also prevent the con-

tact members from sliding forwardly of the insulating body or towards the head of the T-shaped shank, while a rearward sliding is prevented by a finger 19 on each of the contact members, which finger engages a forwardly directed shoulder 20 on the insulating body. To afford such a shoulder, each of the lateral recesses or channels in the insulating body is deepened beginning at a point spaced from its rear end as shown in Figs. 2 and 6, and this deepening is preferably increased towards the forward end of the insulating body so as to permit the portion of the contact members which extend forwardly of the said shoulders 20 to be flexed inwardly. These forwardly extended portions are continued so as to afford contact fingers 21 and 22 extending into the head 6 of the T-shaped shell and into contact respectively with the axial terminals 85 of the two lamp bulbs, such as the lamp terminals 23 and 24 of Fig. 3.

By suitably proportioning the parts, I can readily cause the insulating tube 13 to clamp the two resilient contact members 90 tightly against the insulating core, so that the said body member can initially be assembled to form the unit as shown in Fig. 5. Then the two halves of the shell are slipped over this unit and are connected to it by a single fastening member, such as a rivet 25 extending through aligned bores in the two shell halves, the insulating tube 1 and the insulating body 11. To adapt the spring contact fingers 21 and 22 more readily to possible variations in the length of the lamp bases, I desirably form a lamp-terminal-engaging boss 27 on each of the same.

When the parts are thus assembled, the 105 channeled insulating core 11 and the insulating tube 13 cooperate in affording insulating means affording a pair of longitudinal passages through which the conducting elements respectively extend, each such passage having a rearward portion formed for engaging the corresponding part of one conducting element to prevent transverse movement of the latter and also having a forward portion formed to permit a flexing 110 of the conducting element radially inward or outward of the shank of the shell which houses the said insulating means.

However, I do not wish to be limited to this or other details of the construction and arrangement here disclosed, it being obvious that the same might be modified in many ways without departing from the spirit of my invention or from the appended claims.

Neither do I wish to be limited to a shaping 120 of the shell parts so that the two lamps will extend in alignment with each other, as the same construction might be embodied in a socket designed for holding the lamps at an angle to each other. For example, Fig. 8 shows a section of such a socket arranged 125

for holding the two lamp bulbs substantially at right angles to each other and oblique to the axis of the wire-terminal plug, the spring contact fingers 30 and 31 being suitably bent so as to present contact portions which are bowed respectively across the axes of the lamp-holding tubular shell portions 32 and 33.

I claim as my invention:—

10 1. A socket for two incandescent lamps, comprising a T-shaped shell having each end of its head portion provided with formations for interlocking with one lamp, and a body member mounted in the shank of the T-shaped shell; the body member comprising an insulating core, a pair of conducting elements disposed at opposite sides of the core and each having a resilient contact portion disposed for engaging one of the lamps, and 15 an insulating tube housing the core and clamping the conducting elements to the core.

2. A socket for two incandescent lamps, comprising a T-shaped shell having each end 25 of its head portion provided with formations for interlocking with one lamp, and a body member mounted in the shank of the T-shaped shell; the body member comprising an insulating core having a pair of oppositely disposed lateral recesses, a pair of conducting elements each having a shank seated in one of the recesses and each having a resilient contact portion extending into the head portion of the T-shaped shell for engaging one of the lamps, and an insulating tube clamping the shanks of the conducting elements to the core.

3. A socket for two incandescent lamps, comprising a T-shaped shell having each end 40 of its head portion provided with formations for interlocking with one lamp, and a body member mounted in the shank of the T-shaped shell; the body member comprising an insulating core having a pair of oppositely disposed lateral recesses, a pair of conducting elements each having a shank seated in one of the recesses and each having a resilient contact portion extending into the head portion of the T-shaped shell for engaging one of the lamps, and an insulating tube clamping the shanks of the conducting elements to the core, the core and the shanks of the conducting elements having relatively 45 interengaging formations for preventing the said shanks from moving either longitudinally or circumferentially of the core.

4. A socket for two incandescent lamps, comprising a T-shaped shell having each end 50 of its head portion provided with formations for interlocking with one lamp, and a body member mounted in the shank of the T-shaped shell; the body member comprising an insulating core having a pair of oppositely disposed lateral recesses, a pair of conductors each having a shank seated in

one of the recesses and each having a resilient contact portion extending into the head portion of the T-shaped shell for engaging one of the lamps, and an insulating tube clamping the shanks of the conducting elements to the core; each of the conducting elements having the end nearest to the foot of the T-shaped shell bent inwardly of the shell to afford a contact tip.

5. A socket for two incandescent lamps, comprising a T-shaped shell having each end of its head portion provided with formations for interlocking with one lamp, and a body member mounted in the shank of the T-shaped shell; the body member comprising an insulating core having a pair of oppositely disposed lateral recesses, a pair of conductors each having a shank seated in one of the recesses and each having a resilient contact portion extending into the head portion of the T-shaped shell for engaging one of the lamps, and an insulating tube clamping the shanks of the conducting elements to the core; each of the conducting elements having the end nearest to the foot of the T-shaped shell bent inwardly of the shell to afford a contact tip and to prevent the said conducting element from sliding toward the head of the shell, and having another portion formed for engaging a part of the insulating core to prevent the said element from sliding away from the said head.

6. A socket as per claim 2, in which the core has oppositely directed shoulder formations respectively facing towards and away from the head of the shell, and in which each conducting element has a pair of portions respectively engaging such oppositely directed shoulder formations to prevent the conducting element from moving either toward or away from the head of the shell.

7. A socket for two incandescent lamps, comprising a substantially T-shaped shell having each end of its head provided with formations for interlocking with one lamp, and a body member mounted in the shell; the body member comprising an insulating core disposed within the stem of the T-shaped shell and provided with a pair of oppositely disposed longitudinal channels, a pair of conducting elements extending respectively through the two channels and each having one end extending into the head of the shell for contacting with one of the lamps, and means for fastening the insulating core to portions of the conducting elements adjacent to the other ends of the latter; the channels being deepened adjacent to the head of the shell to permit the lamp-contacting portions of the conducting elements to be flexed towards each other.

Signed at Chicago, Illinois, January 31, 1924.

CHARLES E. GODLEY.
